UNITED STATES PATENT OFFICE

2,458,137

TOY TYPEWRITER

Samuel I. Berger, Newark, N. J.

Application January 24, 1947, Serial No. 724,043

9 Claims. (Cl. 197—47)

1

It is among the objects of my present invention to provide a toy typewriter which has all the advantages of that of my previous application Serial No. 658,318, filed March 29, 1946 and of my previous issued Patent No. 2,398,765, dated April 23, 1946, including the use substantially solely of sheet metal and rod stock to simulate the appearance of a genuine portable typewriter and to do so by a structure that is more attractive in appearance, simpler in construction, affording greater convenience in operation and enhanced reliability in use and which has the further advantage over said prior inventions of increased visibility of the typing area of the platen.

In the accompanying drawings in which is shown one of various possible embodiments of the several features of the invention,

Fig. 1 is a plan view of a toy typewriter according to the present invention showing its general appearance with the simulated keyboard and associated structure in place thereon,

Fig. 2 is a transverse sectional view thereof taken along line 2—2 of Fig. 1,

Fig. 3 is a view similar to Fig. 2 with the key lever depressed, showing the type wheel in typing position,

Fig. 4 is a transverse sectional view taken on line 4—4 of Fig. 1,

Fig. 5 is a transverse sectional detail view taken on line 5—5 of Fig. 4, and

Fig. 6 is a sectional detail view taken on line 6—6 of Fig. 5.

Referring now to the drawings, the toy typewriter simulates the general appearance of a modern portable typewriter, presenting as it does a base 11, a simulated standard keyboard 12, a housing 13 to the rear thereof of the shape and dimensions commonly used on standard typewriters to enclose the key lever basket and the ribbon mechanism, and a platen structure 14 to the rear of the housing.

The sham keyboard and housing are preferably of a single sheet metal stamping, the housing portion being divided as at 15 to accommodate the main operating parts of the toy typewriter which are mounted on an oblique rectangular platform 16 which is a unitary part of the base. The platform has a short front wall 17, a higher rear wall 18 and trapezoidal side walls 19.

Protruding from the divided portion 15 of the housing is a single U-shaped key lever 20, depression of which effects the typing operation by the means hereinafter described.

Upon the middle of the platform 16 is affixed a standard, preferably a U-shaped sheet metal

bracket 21 having a pair of upstanding arms 22, 23 at opposite ends on each side thereof. Key lever 20 is pivoted on an axle 24, the latter being journaled in arms 22 of the bracket 21. Each of the arms 25 of the key lever 20 is pivoted to a link 26, the upper end of said link being pivoted by means of axle 27 to the obliquely extending arms 28 of a substantially U-shaped sheet metal carriage 29. The end of each of said oblique arms 28 is pivoted to upstanding arms 23 on standard 21 as at 59.

Depending from carriage 29 is a U-shaped bracket 30, the arms of said bracket being affixed to the carriage 29 as at 31. A type wheel 32 having at its periphery the type heads comprising the sequence of letters and numerals, is affixed to the upper end of a substantially upright axle 35, the latter in position of rest being at substantially right angles to platform 16 and journaled in bearing openings 33, 34 in bracket 30 and carriage 29 respectively and protruding from the latter.

The type wheel 32 is adjusted to a selected setting by means of a rotatable dial knob 36 which bears the sequence of letters and numerals on its upper surface. The dial knob is affixed to the upper end of shaft 35 as by force fit in its hub 35' and its upper surface is exposed at the exterior of the housing 13, as best shown in Figs. 1 and 4. Ratchet means is preferably provided to step the type wheel around in effective setting thereof by the turning of dial knob 36. A pointer 55 which indicates the selected setting is positioned so as to be near the periphery of said knob. It is affixed to a cover plate 29', the latter being supported by carriage 29 and depending therefrom and enclosing the operating mechanism. The ratchet means preferably comprises a horizontal ratchet wheel 37 interposed between bracket 30 and type wheel 32 and keyed as at 38 upon type wheel axle 35. The ratchet wheel is provided with teeth 39, the interdental spaces of which correspond to the respective characters and numerals on the dial knob and type wheel.

Coacting with the ratchet wheel is a pawl lever 40 which is pivotally mounted at one end to bracket 30 and which bears a pawl roller 41 near its opposite end urged by coil spring 42 into engagement between the teeth of the ratchet. The pawl roller 41 is preferably pivoted on a pivot 43, as best shown in Fig. 6, in a clevis formed between the main length of the pawl lever and the reversely turned extremity of the lever. The coil spring is preferably anchored at one end to pivot 43 at the roller end of the pawl lever and

at its other end to the lower end of axle 35 on which the type wheel and dial knob are mounted.

For applying ink to the type head, an ink retaining absorbent roller 44 which is itself conventional is preferably provided. This roller is mounted on a bail 49 integral with and extending outward from the midsection of the cross-arm of a substantially U-shaped bracket 45, the arms 46 and 47 of which are pivoted to the carriage 29 as at 48. The extension 46 of arm 46 is connected by pitman 58 to arm 22 of bracket 21 for the purpose hereinafter described. The bail 49 has a slot 51 in each of its cross-arms 50. Mounted in said slots 51 is a wire spring holder 52 with two legs 53 and 54 resiliently urged apart by the connecting loop 56. Leg 54 extends through a sleeve 57 upon which the ink roller 44 is mounted. Accordingly, the spring holder may readily be withdrawn for replacement of the ink roller as required. In the normal or idle position of the machine, the ink roller is in engagement with the type wheel as best shown in Figs. 2 and 4.

The escapement structure is quite similar to that of my above identified issued patent and need therefore be but briefly described. The escapement box 60 is conventional and its interior parts are not shown. Its protruding pawls 61 coact with an indented rack 62 (Figs. 2 and 4) on the base of the platen structure. The escapement is operated from a cam plate 63 freely rotatable about the axle 24 of the key lever and connected by a wire link 64 hooked at 65 to plate 63 at one end and to the mechanism in the escapement box 60 at the other. A link 66 pivoted at one end to carriage 29 on axle 27 and having a stud 67 at its other end riding in an arcuate slot 68 in the cam plate causes the latter to be pivoted by the depression stroke of the key lever 20, thereby to pull link 64 forward for the escapement action.

The spacer lever 69 protruding through the forward part of the platform 16 is pivotally anchored at its rear end as at 70 to the rear wall 18. An upstanding link 71 is pivotally connected at its lower end to spacer lever 69 as at 72. The upper end of link 71 is pivoted in an arcuate slot 73 in cam plate 63 into which slot it is hooked as at 74, riding idly therein when key lever 20 is depressed and actuating the escapement mechanism through link 64 when spacing lever 69 is depressed.

The operation may be briefly summarized. The dial knob 35 is first turned to the desired letter or numeral as indicated by the pointer 55. This turns the type wheel 32 which is affixed to the same axle 35 as is the dial knob. In reaching the desired setting, the ratchet wheel 37, which is also keyed on axle 35 ratchets over the roller 41 of the spring urged pawl lever 40, the latter resiliently holding the ratchet wheel and with it, the type wheel 32, in the set position.

Key lever 20 is now depressed, causing it to pivot about axle 24. The thrust transmitted from the key lever through links 26 to carriage 29 causes the latter to pivot upwardly about its pivots 59 from the standby position shown in Fig. 2 to the position shown in Fig. 3, bringing the type wheel 32 in contact with the paper on the platen 14.

In the course of the depression of the key lever 20, bracket 45 carrying roller 44 is pivoted by means of pitman 58 causing roller 44 to be raised, inking a few of the type heads including the one to be imprinted during its upward motion, and then clearing the type wheel and the platen.

Depression of key lever 20 also causes link 66 to be moved toward the platen 14 by the transmission 26, 27, thereby causing cam plate 63 to turn in a clockwise direction, as seen in Figs. 2 and 3 through the transmission 67, 68. This will cause link 64 to be pulled, thereby moving the platen forward one space.

Release of the key lever will allow the carriage to pivot to its idle position, as shown in Fig. 2, solely by virtue of the weight of the carriage. Return of the carriage will also cause the bracket 45 to pivot downward to the position shown in Fig. 2, again placing the ink roller in contact with the type wheel.

The spacer lever 69 when depressed, will cause link 71 to rotate the cam plate causing the escapement mechanism to function. Due to the lost motion slot 68, depression of the spacer lever will have no effect on carriage 29.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. In a typewriting mechanism, the combination of a base, a platen structure at the rear part thereof, a carriage pivoted on said base, a type wheel having a substantially upright axle bearing in said carriage, a rotatable dial knob affixed to the upper end of said axle, a ratchet wheel on said axle coaxial and rigid with said type wheel and said knob, a spring, pressed pawl lever pivoted to said carriage and coacting with said ratchet wheel for resiliently retaining the type wheel in set position, and a pointer on said carriage coacting with said knob to indicate the setting thereof.

2. In a typewriting mechanism, the combination of a base, a platen structure at the rear part thereof, a carriage pivoted on said base, a type wheel having a substantially upright axle bearing in said carriage, a rotatable dial knob affixed to the upper end of said axle, a ratchet wheel on said axle coaxial with and rigid with said type wheel and said knob, a spring, pressed pawl lever pivoted to said carriage and coacting with said ratchet wheel for resiliently retaining the type wheel in set position, a pointer on said carriage coacting with said knob to indicate the setting thereof, and means for rocking said carriage to imprint the selected type against the platen.

3. In a toy typewriter, a base, a platen structure rising from the rear thereof, a standard in front of said platen, a carriage pivoted in said standard, a substantially upright axle bearing in said carriage and having affixed theron in coaxial relation therewith a ratchet wheel, a type wheel and a dial knob, the latter being affixed to the upright axle at the upper end thereof, means for rocking said carriage to typing position, said means comprising a key lever pivoted to the standard and a link connecting said key lever to said carriage for tilting the latter, a pawl lever pivoted to said carriage and having a ratchet wheel engaging roller near the free end thereof, and a spring urging the roller end of said lever against the periphery of said ratchet wheel.

4. The combination set forth in claim 3 in which said carriage is constructed and arranged

so as automatically to return to standby position after said key lever has been released.

5. In a toy typewriter, the combination of a base, a platen structure rising from the rear thereof, a standard rising from said base and in front of said platen structure, a carriage pivoted in said standard, a type wheel having a substantially upright axle bearing in said carriage, a ratchet wheel coaxial with and affixed to the lower part of said axle, a pawl lever pivoted to said carriage at the outer side thereof and having a roller near its free end, a spring resiliently urging said roller against the periphery of said ratchet wheel, a rotatable dial knob affixed to the upper end of said upright axle, a sequence of letters and numerals peripherally about said knob, and a pointer near the periphery of said knob and affixed to said carriage.

6. In a typewriter of the character comprising a base having a platform, a platen structure, a type wheel having a substantially upright axle at right angles to said platform, a pivoted carriage mounting said type wheel, a bracket pivotally mounted on said carriage and straddling said type wheel, an inking roller rotatably mounted on said bracket, and means linking said bracket to said base for displacement of said roller in the forward rocking of the carriage toward the platen, thereby moving the roller across the type of the type wheel during the typing stroke and clearing the path of movement of the selected type toward the platen.

7. In a toy typewriter, the combination of a base, a platen structure rising from the rear thereof, operating mechanism on said base, said mechanism comprising a standard rising from said base and in front of said platen structure, a carriage pivoted on said standard, means for rocking said carriage to typing position, a type wheel having a substantially upright axle bearing in said carriage, a ratchet wheel coaxial with and affixed to the lower part of said axle, a pawl lever pivoted to said carriage at the outer side thereof and having a roller near its free end, and a spring resiliently urging said roller against the periphery of said ratchet wheel, a cover plate supported by said carriage and depending therefrom and en-

closing said operating mechanism, a rotatable dial knob affixed to the upper end of said upright axle, a sequence of letters and numerals peripherally about said knob, and a pointer near the periphery of said knob and affixed to said carriage.

8. In a toy typewriter, a base, a platen structure rising from the rear thereof, a standard in front of said platen, a carriage pivoted in said standard, a bracket depending from said carriage and affixed thereto, a substantially upright axle bearing in said bracket and said carriage and protruding from the latter, said axle having affixed thereon in coaxial relation therewith a ratchet wheel and a type wheel between said bracket and said carriage, a dial knob affixed to said upright axle on the protruding end thereof, a pawl lever pivoted to said bracket and having a ratchet wheel engaging roller near the free end thereof, a spring urging the roller end of said lever against the periphery of said ratchet wheel, and means for rocking said carriage to typing position.

9. The combination set forth in claim 8 in which means are provided for applying ink to said type wheel, said means comprising a bracket pivotally mounted on said carriage and straddling said type wheel, an inking roller rotatably mounted on said bracket, and means linking said bracket to said base for displacement of said roller in the forward rocking of the carriage toward the platen, thereby moving the roller across the type of the type wheel during the typing stroke and clearing the path of movement of the selected type toward the platen.
